CONTROL SYSTEM

Frederic M. Roberts and Lucius A. Norris,
Schenectady, N. Y., assignors to General Electric Company, a corporation of New York

Application June 29, 1940, Serial No. 343,256

8 Claims. (Cl. 242—55)

This invention relates to control systems, more particularly to systems for controlling the winding of a predetermined length of material on a roll, and it has for an object the provision of a simple, reliable and improved control system of this character.

Certain materials such as paper towelling, and toilet paper are unwound from a large supply roll, perforated to form sheets and are then rewound on rolls which are offered for sale with a statement on the roll wrapper that the rolls contain a predetermined number of sheets. For example, rolls of paper towelling usually contain 150 sheets and rolls of toilet paper usually contain 1000 sheets. The rolls must contain at least as many sheets as the number stated on the wrapper, but any excess over this number represents a loss to the manufacturer. Consequently, a further object of the invention is the provision of means for accurately counting the number of sheets on the roll.

If any time is lost in winding a roll a maximum economy in production is not realized. A large factory may produce many millions of rolls of the product in a year. Even if only a few seconds of time be lost in the winding of each roll, the total loss for the year becomes a very large and important item. Accordingly, an object of the invention is the provision of means for winding the exact number of sheets on the roll in the minimum possible time consistent with the maximum winding speed and the maximum permissible rate of acceleration and deceleration. Stated in other words, the roll must be accelerated at the maximum permissible rate, operated at the maximum permissible speed until such time in the winding operation that deceleration beginning at such time and continuing at the maximum permissible rate will stop the roll with the exact desired number of sheets on the finished roll.

At the present time, even in the most modern manufacturing plants, the counting of sheets on a roll is done by operators who observe a counting device and use their judgment as to the correct instant for initiating the deceleration. Even the best operators do not succeed in stopping the roll at the instant when it contains the exact desired number of sheets. If the roll stops with too many sheets a loss results, and if it stops with too few sheets the drive must be restarted and again stopped, which introduces a time loss and when stopped the second time the roll may contain too many sheets which results in a material loss in addition to the time loss.

Accordingly, a further object of the invention

5 is the provision of a control system of the character described in the foregoing in which the deceleration and stopping operation is entirely automatic and errors resulting from human judgment are eliminated.

When the supply roll is full its inertia is relatively large and "snap off" occasioned by too rapid acceleration rates occurs frequently. This, of course, results in a loss in material and in a loss of the time required for rethreading as well as of the time consumed between the finish of the previous roll and the time of the "snap off." Also, if the rate of deceleration is too great a loop is formed between the supply roll and the winding roll and this loop may come in contact with the floor and thus result in another loss of time and material.

Accordingly, a still further object of the invention is the provision of means for limiting the acceleration and deceleration to maximum permissible rates.

In carrying the invention into effect in one form thereof, an electric motor is provided to wind the roll. This motor is supplied from an 25 adjustable voltage generator. A limit switch driven in accordance with the travel of the material operates to weaken the field of the generator to initiate deceleration of the roll drive motor when a given amount of material is wound 30 on the roll and operates to disconnect the generator field winding and to reconnect it to the armature with reverse polarity so that the roll drive motor will be brought to rest when a predetermined length of material containing the exact 35 desired number of sheets is wound on the roll.

For a better and more complete understanding of the invention, reference should now be had to the following specification and to the accompanying drawings in which Fig. 1 is a simple, diagrammatic sketch of winding apparatus of the character described in the foregoing, Fig. 2 is a simple, diagrammatical sketch of an embodiment of the invention, Fig. 3 is a sketch of a detail of the invention, and Fig. 4 is a chart of operating characteristics which facilitate an understanding of the invention.

Referring now to the drawings, a strip of material 10, which may be assumed to be paper towelling, is unwound from a full supply roll 11 and is passed through a tensioning device comprising two idler rolls 12 and 13, and a weighted roll 14 which rides in a loop formed in the material between the idler rolls 12 and 13. From the tensioning device, the material is passed over an idler roll 15 and then through a device 16 which

perforates the material in individual sheet lengths, after which the material is wound on a roll 17. It is desired to effect the operation of winding the sheets on the winding roll 17 in a minimum of time and to stop the operation when a predetermined number of sheets is on the roll so that the finished roll, which is offered for sale, will contain no more and no less than the exact number of sheets printed on the wrapper.

The idler roll 15, the perforating device 16, and the winding roll 17 are driven by suitable driving means such as an electric motor 18. As shown, this motor is supplied from an adjustable voltage generator 19 which in turn is driven by a suitable driving means such as an induction motor (not shown) at a speed which is preferably substantially constant. The generator 19 is provided with a commutating field winding 19a and a series field winding 19b and is also provided with a separately excited shunt field winding 19c. The generator field winding 19c is excited from a suitable source of excitation such as the excitation busses 20 and 21 which are supplied from an exciter 22. A rheostat 24 is connected in circuit with the separately excited field winding 19c. This rheostat serves to adjust the maximum armature voltage of the generator 19 and therefore the maximum speed of the motor 18, which is supplied therefrom, to any desired value.

For the purpose of limiting the rate of rise and decay of the flux of the generator field 19c and therefore the rate of acceleration and deceleration of the winding motor 18, to a maximum permissible value, an energy storage device 25 is provided. This energy storage device may take the form of a dynamo-electric machine 25, having its armature terminals arranged to be connected in parallel with the separately excited generator shunt field winding 19c. It is also provided with flywheel capacity for storing mechanical energy. The dynamo-electric machine 25a is illustrated as being provided with an external flywheel 25b but it will be understood, of course, that the flywheel may be built into the rotor of the dynamo-electric machine 25a.

The dynamo-electric machine 25a is provided with a separately excited shunt field winding 25c which is connected to the excitation busses 20 and 21. During the rise of magnetic flux in the generator shunt field winding 19c, i. e., during acceleration of the roll winding motor 18 the dynamo-electric machine 25a operates as a motor and stores energy in the flywheel 25b. A variable resistor 26 is included in circuit with the field winding 25c and this variable resistor serves to adjust the maximum speed of the dynamo-electric machine 25a and therefore the amount of energy stored in the flywheel 25b to any desired value within a wide range of values.

A pair of adjustable resistors 27 and 28 are provided and are arranged to be selectively connected in the circuit of the generator shunt field winding 19c under certain operating conditions by means of a selector switch 29. The resistor 27 has a low resistance and the resistor 28 has relatively high resistance. Switching device 29 is provided with an operating coil 29a which is designed to be connected across the excitation busses 20 and 21 when the "start" switching device 30 is depressed to bridge normally open contacts 30a. The starting device is illustrated as a manually operated switching device of the push button type.

A switching device illustrated as an electro-

magnetic contactor 31 is provided for controlling the connections of the generator shunt field winding 19c and of the armature of the flywheel dynamo-electric machine 25a. When the contactor 31 is operated to its upper position the generator shunt field winding 19c is connected across the excitation busses 20 and 21 and the armature of the flywheel dynamo-electric machine 25a is connected in parallel with the generator shunt field winding 19c, whereas when the contactor 31 is in the dropped-out position in which it is illustrated, the generator shunt field winding 19c is disconnected from the excitation busses 20 and 21 and is connected across the armature terminals of the generator with reverse polarity and the armature of the flywheel dynamo-electric machine 25a is disconnected from the generator shunt field winding.

In order to provide short "inching" or "jogging" movements a "jog" relay 32 and a "jog" push button type switch 3 controlling the energization of the operating coil of the "jog" relay are provided. When the jog switch 33 is depressed, the jog relay 32 is picked up and this in turn causes the field relay 31 to be picked up to connect the generator shunt field winding 19c to the excitation busses 20 and 21 with the high resistance resistor 28 included in circuit so that the generator generates a very low voltage and the winding motor 18 is caused to operate at a steady slow speed.

For the purpose of counting the number of sheets on the winding roll and for initiating the deceleration and stopping of the winding roll motor 18 at predetermined points in the winding cycle so that the roll will be brought to rest with the desired exact number of sheets wound thereon, a suitable limit switch mechanism 34 is provided. This limit switch device 35 comprises a rotatable member illustrated as a splined shaft 35 which is connected to be driven in accordance with the travel of the paper 10. In Fig. 1, the limit switch is illustrated as being driven from the shaft of the perforating device 16. As shown in Fig. 3, the limit switch is provided with an electromagnetic clutch 36 which is included in the driving connections between a rotatable splined member 35 and the shaft of the perforating device 16. The electromagnetic clutch 36 is normally disengaged, i. e., its contact surfaces are normally separated when the clutch solenoid 37 (Fig. 2) is deenergized. Limit switch 34 is also provided with a supporting casting 38 and a cover 39 which also acts as a supporting member for certain parts of the limit switch. A pair of micro-switches 40 and 41 or other suitable contacts are mounted on the casting 38 as shown in Fig. 3. Since the structural details per se of these switches constitute no part of the present invention, only the casings of these switches are illustrated in Fig. 3. However, the micro-switch 40 is provided with a pair of normally closed contacts 40a and micro-switch 41 is provided with a pair of normally closed contacts 41a (Fig. 2). It will be noted that a pin 40b of switch 40 projects through the casings into contact with a spring lever 40c. Whenever the spring lever 40c is displaced by an amount as small as .001 inch, pin 40b moves sufficiently to separate the contacts 40a. Although not shown, it will be understood that the contacts of the micro-switch 40 are of the over-center snap action type. Switch 41 is also provided with pin 41b and a spring lever 41c which are identical with the corresponding parts of switch

40. It will be noted that the casings of the switches 40 and 41 are pivotally mounted so that each of these switches can be rotated out of the vertical position in which they are illustrated against the action of springs 42 and 43, respectively. A pair of screws 44 and 45 are threaded through the cover 38 so that their axes are parallel to the longitudinal axis of the rotatable splined member 35. A pair of nuts 46 and 47 are threaded on the screws 44 and 45, respectively. These nuts 46 and 47 are provided with external gear teeth which mesh with the splines on the rotatable member 35 so that the nuts 46 and 47 travel along the screws 44 and 45 in response to rotation of the splined member 35. At a predetermined point in its travel along the screw 44, the nut 46 engages the spring lever 40c and causes the contact 40a to open. Similarly, at a predetermined point in its travel along the screw 45, the nut 47 engages the spring lever 41c and opens the contacts 41a. It will be noted that the heads of the screws 44 and 45 are recessed to provide more adjustment by means of a screw driver.

At the beginning of the roll winding operation, the nuts 46 and 47 occupy the dotted line positions indicated in Fig. 3. As the winding operation progresses the nuts 46 and 47 are driven by the splined member 35 and travel to the right to engage the spring levers 40c and 41c to effect deceleration and stopping of the roll winding motor 18. Limit switch 34 is provided with a spring member 48 which is wound up by the rotatable splined member 35 during the progress of the winding operation. When the winding operation is completed and the clutch solenoid 37 is deenergized to effect disengagement of the clutch, the spring 48 returns the rotatable splined member 35 to its original position and consequently the traveling nuts 46 and 47 are returned to their original positions which are illustrated in dotted lines in Fig. 3.

With the foregoing understanding of the elements and their organization in the system, the operation of the system will be readily understood from the description which follows:

It is assumed that the exciter 22 is being driven at normal speed and is generating its normal full line voltage. The end of the paper 10 is secured to the winding roll 17. To start the winding operation the "start" button 30 is depressed to close the contacts 30a. This completes an energizing circuit for the operating coil 29a of the selector switch 29. This energizing circuit is traced from the side 20 of the excitation source through the "stop" push button switch 49, contacts of the "start" push button switch 30, operating coil 29a of the selector switch 29, normally closed contacts 40a and 41a of limit switch mechanism 34 to the side 21 of the excitation source. Selector switch 29 in responding to energization of its operating coil closes its normally open contacts 29b, 29c, 29d, and 29e and opens its normally closed contact 29f. In the closed position of contacts 29b, a holding circuit for the operating coil 29a is established in parallel with the contacts of the "start" push button 30 which may now be released. Contacts 29c when closed complete an energizing circuit for the operating coil 50a of a sequencing control relay 50 through the normally closed contacts 41a of the limit switch. Similarly, contacts 29d in closing complete an energizing circuit for the operating coil 51a of another control relay 51. This circuit is traced from the side 20 of the excitation source

through contacts 29d, operating coil 51a of relay 51, through normally closed contacts 41a of the limit switch to the side 21 of the excitation source. Relays 50 and 51 in responding to energization close their normally open contacts 50b, 50c, and 50d and 51b, 51c and 51d, respectively. Contacts 50b in closing complete a holding circuit for the operating coil 50a in parallel with the contacts 29c so that relay 50 will remain picked up if the contacts 29c of relay 29 are subsequently opened. Similarly, in the closed position of contacts 51a, a holding circuit for the operating coil 51a of relay 51 is established in parallel with the contacts 29d so that relay 51 will remain picked up after the contacts 29d are opened. Contacts 50c of relay 50 and contacts 51b of relay 51 cooperate to complete an energizing circuit for the operating coil 31a of the generator field contactor 31. This circuit is traced from the side 20 of the excitation source through the normally closed contacts of the "jog" push button 33, contacts 50c of relay 50, normally closed contacts 32a of "jog" relay 32, contacts 51b of relay 51, operating coil 31a of the field contactor, through normally closed contacts 41a of the limit switch to the side 21 of the excitation source.

Field contactor 31, in responding to energization, opens its normally closed contacts 31b and 31c and closes its normally open contacts 31a, 31e and 31f. Contacts 31a in their closed position connect the armature of the flywheel dynamo-electric machine 25a in parallel with the separately excited generator shunt field winding 19c. At the same time contacts 31e and 31f connect the generator shunt field windings 19c to the excitation source 20 and 21 through the low resistance resistor 27 and the speed rheostat 24 which has previously been adjusted for the maximum operating speed of the winding motor 18. The flux of the generator field winding 19c begins to rise and continues to rise at a rate which is dependent upon the electrical constants of the generator shunt field circuit and the mechanical and electrical constants of flywheel dynamo-electric machine 25a. As the generator flux begins to rise, the armature voltage begins to build up and the winding motor 18 begins to accelerate. The closing of contacts 51d of contactor 51 connects the clutch solenoid 37 across the excitation source 20 and 21 and in response to the energization of this solenoid, the clutch is engaged and the splined member 35 begins to rotate. In consequence of the rotation of the member 35, spring 48 begins to wind up and the nuts 46 and 47 begin to travel to the right along threaded screws 44 and 45. The electrical constants of the generator shunt field winding 19c and the mechanical and electrical constants of the flywheel dynamo-electric machine 25a are so chosen that the acceleration of the motor 18 is limited to a maximum permissible value. This acceleration to the maximum operating speed is represented graphically in Fig. 4 by the portion 52 of the curve whose ordinates represent speed and whose abscissae represent time. When the acceleration is at the maximum permissible rate, the maximum operating speed is reached in a minimum time. Thereafter, the winding operation continues at maximum speed as represented by the flat portion 53 of the curve in Fig. 4. As the winding operation continues, the splined member 35 continues to wind up the spring 48 and the nuts 46 and 47 continue to travel to the right.

At a predetermined point in the winding operation, which is represented by the point T₁ on the

graph in Fig. 4, i. e., when a given amount of the material 10 is wound on the roll 17 the traveling nut 46 strikes the spring lever 40, with the result that spring lever 40, moves to the right and presses on the pin 40_b which separates the contacts 40_a of the limit switch. As a result of the opening of contacts 40_a, the operating coil 29_a of selector switch 29 is deenergized and this switch opens its normally open contacts and closes its normally closed contacts 29_b. Relays 50 and 51 whose energizing circuits were completed through contacts 29_a and 29_b of switch 29 do not drop out since their operating coils remain energized through holding circuits established by their own auxiliary contacts 50_b and 51_b respectively.

When contacts 29_a are open the low resistance resistor 27 is removed from the circuit of the generator shunt field winding 19_b and when the contacts 29_b are closed the high resistance resistor 28 is inserted in the circuit of the generator shunt field winding. As a result of this the field strength of the generator is weakened and deceleration of the winding roll motor 18 is initiated. With respect to the decay of exciting current in the generator shunt field winding 19_c the flywheel dynamo electric machine 25_a operates to limit the rate of decay of flux in the following manner. The exciting current of the field winding 19_c tends to be maintained not only by the action of its own self-induced counter E. M. F. but also by the counter E. M. F. of the flywheel machine 25_a which is now driven as a generator by the kinetic energy stored in its own armature or flywheel. As a result, it serves in large measure to control the rate of change of excitation of the winding 19_c during the period of decay and prolongs the decay very substantially in comparison with that which would be provided solely by the electromagnetic stored energy of the winding 19_c.

The running light current of the dynamo electric machine 25_a when operating as a motor being very small and the resistance of its armature also being very small, the initial counter E. M. F. of the motor 25_a at the instant of opening the switch contact 29_e is practically equal to the IR drop of the field winding 19_c. Hence the self-induced voltage of the field winding 19_c is very small at this instant and as a result the initial rate of decay of its exciting current is also very small. It will thus be seen that the kinetic stored energy of the motor 25_a and its flywheel 25_b supplies most of the energy and excitation during the initial part of the decay. As the motor 25_a slows down, its counter E. M. F. decays quite rapidly thus permitting the rate of decay of the exciting current of winding 19_c to increase. This, however, causes the self-induced voltage of the winding 19_c to increase which in turn acts to restrict the rate of decay of flux of the winding 19_c so that it is less than proportional to the decay of the counter E. M. F. of the motor 25_a.

The total effect then is that the decay of exciting current in the field winding 10 begins at a very moderate rate, rises quite gradually to a maximum rate and then gradually diminishes to lower rates of decay as the transient approaches completion.

The decay of flux of the generator shunt field winding 19_c produces a corresponding decay of the generator voltage and a corresponding deceleration of the winding roll motor 18. The deceleration of the winding roll motor is indicated in

the graph by the sloping portion 54 of the speed curve.

During the deceleration of the motor 18, the traveling nut 46 continues to travel toward the right on the threaded screw 44. The switch casing of the microswitch 40 pivots in a clockwise direction about its pivot to permit the nut 46 to continue its travel during the deceleration.

The deceleration of the winding roll motor 18 continues until a point T₂ in the operation is reached at which the speed of the motor is almost zero and the number of sheets wound on the roll 17 is almost the desired exact number. At this time T₂, traveling nut 47 strikes the spring lever 41_c and causes it to move to the right to push on the pin 41_b so as to open the limit switch contacts 41_a. Contacts 41_a in opening interrupt the energizing circuits for the operating coil 31_a of the field contactor 31, and contactor 31 in response to deenergization opens its normally open contacts 31_a, 31_b and 31_c and closes its normally closed contacts 31_d and 31_e. Contacts 31_d and 31_e in opening disconnect the field winding 19_c from the excitation source 20 and 21 and contact 31_d in opening disconnects the armature of the flywheel dynamo electric machine 25_a from the generator shunt field winding 19_c. Contacts 31_b and 31_c in closing reconnect the generator shunt field winding 19_c to the armature terminals of the generator 19 with reverse polarity so that the armature voltage of the generator tends to cause current to flow in the opposite direction through the shunt field winding 19_c. As a result of this the flux of the shunt field winding 19_c decays very rapidly towards zero. Likewise the armature voltage of the generator 19 decreases rapidly towards zero. When the flux of the field winding 19_c reaches zero value the voltage of the generator also reaches zero value and consequently this reverse connection does not cause the generator field to build up in the reverse direction.

The decrease of the armature voltage to zero also causes the speed of the winding roll motor 18 to decrease to zero and this zero speed of the winding roll motor 18 is reached when the exact desired number of sheets of the material 10 are wound on the roll 17. It will be understood, of course, that several trial adjustments of the screws 44 and 45 may be necessary in order to position the traveling nuts 46 and 47 so that they will initiate deceleration at the proper time to stop the roll 17 when it contains exactly the desired number of sheets.

The opening of contacts 51_d deenergizes the clutch solenoid 37 and this results in disengaging the clutch 36. When the clutch 36 is disengaged, the spring 48 which was wound up by the rotation of the splined member 35 is now free to rotate splined member 35 in the opposite direction. As a result, the spring 48 rotates the splined member the exact number of turns in the reverse direction that it was rotated in the forward direction during the roll winding operation and consequently when the spring 48 is completely unwound the splined member 35 will be in its original position and likewise the traveling nuts 46 and 47 will be in their original positions. As the nuts 46 and 47 back away from the micro-switches 40 and 41 the springs 42 and 43 return to their original position and thus the limit switch mechanism 34 is left in a reset condition for a subsequent operation.

When limit switch contacts 41_a open, the energizing circuits for relays 50 and 51 are interrupted

and these relays drop out thereby to restore the system to its original condition so that it is reset for a subsequent winding operation.

Under certain operating conditions it may be desirable to stop the winding operation at an intermediate point before the complete number of sheets is wound on the roll. This is accomplished by depressing the stop button 49 to interrupt the energizing circuit for the operating coil of contactor 20. In response to deenergization contactor 20 drops out to open contacts 29_a and close contacts 29_b. Contacts 29_a in opening remove the low resistance resistor 27 from the circuit of the generator shunt field winding 18, and contacts 29_b in closing insert the high resistance resistor 28 in the circuit of the generator shunt field winding 18 to initiate the deceleration. Depressing the stop button 49 also interrupts the energizing circuit for the operating coil 50_a of relay 50 and this relay in response to deenergization opens its normally opened contacts 50_b, 50_c, and 50_d. Contacts 50_d in opening do not interrupt the energizing circuit for the operating coil 31_a of the field contactor 31 since the contacts 50_d are paralleled by the contacts 55_a of the counter-voltage relay 55 and the contacts 55_a are bridged by the movable contact member of this relay which is held in its upper position as long as the counter-voltage of the motor 18 is greater than a predetermined value. As soon as the deceleration of the motor 18 reaches such a point that its counter-voltage decreases below this predetermined value, the counter-voltage relay 55 drops out and opens contact 55_a thereby to interrupt the energizing circuit for the operating coil of field contactor 31. In response to deenergization contactor 31 disconnects the generator shunt field winding 18 from the excitation source 20 and 21 and reconnects it to the generator armature with reverse polarity to effect the final stopping of the motor 18 in the same manner as that described in the foregoing.

When the stopping is thus effected manually, the energizing circuit for the operating coil 51_a of relay 51 is not interrupted and consequently the clutch solenoid 37 is not deenergized. As a result there is no resetting of the limit switch mechanism 35 such as occurs when the deceleration and stopping of the unwinding roll motor are initiated by the limit switch itself. If the limit switch were reset when its stopping is effected manually and the winding operation were to be resumed by pressing the start button 30, the final amount of material on the roll 17 would be equal to a full roll plus the amount that had been already wound on the roll when the stop button was depressed. This, of course, would represent a loss of material.

Thus by arranging the control so that the limit switch is not reset when it is necessary to interrupt the winding operation, the winding operation can be resumed by depressing the start button 30 and the winding roll motor 18 be stopped automatically by the limit switch when the roll contains the exact desired number of sheets in the manner described in the foregoing.

Although in accordance with the provisions of the patent statutes this invention is described as embodied in concrete form and the principle thereof has been described together with the best mode in which it is now contemplated applying that principle, it will be understood that the elements and apparatus shown and described are merely illustrative and that the invention is not

limited thereto since alterations and modifications will readily suggest themselves to persons skilled in the art without departing from the true spirit of this invention or from the scope of the annexed claims.

What we claim as new and desire to secure by Letters Patent of the United States, is:

1. A control system for apparatus for winding a predetermined length of material on a roll comprising an electric motor for controlling the winding of said material on said roll, an adjustable voltage generator for supplying said motor, a limit switch actuated in accordance with the travel of said material for weakening the field of said generator thereby to initiate deceleration of said motor when a predetermined amount of said material is wound upon said roll and for further weakening said generator field to effect stopping when a different predetermined amount of said material is wound on said roll, and means responsive to the last mentioned operation of said limit switch for resetting said limit switch for a succeeding operation.
2. A control system for apparatus for winding a predetermined length of material on a roll comprising in combination an electric motor for driving said winding roll, an adjustable voltage generator for supplying said motor, said generator having a field winding, a limit switch having a rotatable member connected to be driven in accordance with the travel of said material, an electromagnetic clutch in the driving connections of said rotatable member, a contact and a member driven by said rotatable member for actuating said contact when a given length of said material is wound on said roll, a second contact and means driven by said rotatable member for actuating said second contact when a different given length of material is wound on said roll, and a spring connected to said rotatable member and arranged to be wound up in response to rotation of said rotatable member, means responsive to actuation of said first contact for initiating deceleration of said motor, and means responsive to actuation of said second contact for disconnecting said generator field winding and reconnecting said field winding to the armature of said generator in reverse polarity thereby to effect stopping of said motor when said predetermined length is wound on said roll and for deenergizing said clutch to provide for return of said rotatable member and said driven member to their original positions.
3. A control system for apparatus for winding a predetermined length of material on a roll comprising in combination an electric motor for driving said winding roll, an adjustable voltage generator for supplying said motor, said generator being provided with a field winding, a resistor having low resistance, a resistor having relatively high resistance, a control device and means responsive to operation of said control device for energizing said field winding with said low resistance resistor in circuit to initiate acceleration of said motor, a limit switch driven in accordance with the travel of said material said limit switch having two contacts arranged to be actuated successively, means responsive to actuation of the first of said contacts to be actuated for inserting said high resistance resistor in circuit with said field winding to initiate deceleration of said motor when a given length of material is wound on said roll, and means responsive to actuation of the second of said contacts for disconnecting said field winding and

reconnecting it to the armature of said generator in reverse polarity thereby to effect stopping of said roll motor when said predetermined length of material is wound on said roll.

4. A control system for apparatus for winding a predetermined length of material on a roll comprising in combination an electric motor for driving said winding roll, a control device and means responsive to operation of said device for initiating acceleration of said motor, a limit switch device having a splined rotatable member connected to be driven in accordance with the travel of said material, a clutch included in the driving connections to said rotatable member, a spring connected to be wound up in response to rotation of said rotatable member, a pair of threaded screws, a nut threaded to each screw and having gear teeth engaging the spline of said rotatable member thereby to provide for axial movement of said nuts along said screws and a pair of contacts arranged to be successively actuated by said nuts, means responsive to actuation of the first of said contacts to be engaged for initiating deceleration of said motor when a given amount of said material is wound on said roll, and means responsive to the actuation of said second contact for stopping said motor when said predetermined length of material is wound on said roll and for disengaging said clutch to provide for reverse rotation of said splined rotatable member to return said nuts to their original positions.

5. A control system for apparatus for winding a predetermined length of material on a roll comprising in combination an electric motor for driving said roll, an adjustable voltage generator for supplying said motor, said generator being provided with a field winding, a starting control device for energizing said field winding to initiate acceleration of said winding motor, a limit switch driven in accordance with the travel of said length of material for weakening the field of said generator to initiate deceleration of said motor when a given length of material is wound on said roll and for disconnecting said field winding and reconnecting it to the armature terminals in reverse polarity to effect stopping of said motor when said predetermined length of material is wound on said roll, and an energy storage device connected to said field winding for limiting the rates of rise and decay of the flux of said field winding thereby to limit the acceleration and deceleration of said motor.

6. A control system for apparatus for winding a predetermined length of material on a roll, comprising in combination an electric motor connected to drive said roll, an adjustable voltage generator for supplying said motor, said generator having a field winding, a starting control device and means controlled thereby for energizing said field winding to initiate acceleration of said motor, a limit switch driven in accordance with the travel of said material for weakening the field of said generator to initiate deceleration of said motor when a given length of said mate-

rial is wound on said roll and for disconnecting said field winding and reconnecting it to the armature terminals of said generator with reverse polarity to effect stopping of said motor when said predetermined length of material is wound on said roll, and a dynamo electric machine connected to said field winding and provided with a mechanical energy storage device for limiting the rates of rise and decay of the flux of said generator thereby to limit the rates of said acceleration and deceleration.

7. A control system for apparatus for winding a predetermined length of material on a roll comprising in combination an electric motor connected to drive said roll, an adjustable voltage generator for supplying said motor, said generator having a field winding, a starting control device and means controlled thereby for energizing said field winding to initiate acceleration of said motor, a limit switch driven in accordance with the travel of said material for weakening the field of said generator to initiate deceleration of said motor when a given length of said material is wound on said roll and for disconnecting said field winding and reconnecting it to the armature terminals of said generator with reverse polarity to effect stopping of said motor when said predetermined length of material is wound on said roll, and a dynamo electric machine connected to said field winding and provided with flywheel capacity for the storage of mechanical energy during the rise of flux of said generator field winding and for giving up said energy during the decay of said flux thereby to limit the rates of rise and decay of said flux and the rates of said acceleration and deceleration of said motor.

8. A control system for apparatus for winding a predetermined length of material on a roll comprising in combination an adjustable voltage generator provided with a field winding and a motor supplied from said generator for driving said roll, a limit switch device driven in accordance with the travel of said material for weakening the excitation of said field winding to initiate deceleration of said motor when a given amount of said material is wound on said roll and for disconnecting said field winding and reconnecting it to the armature terminal of said generator with reverse polarity to effect stopping of said motor when said predetermined length of material is wound on said roll, a manually operated control device and means controlled thereby for weakening the excitation of said field winding to initiate deceleration of said motor at any time prior to operation of said limit switch device, and a relay having an operating coil energized by the voltage existing at the terminals of said motor for disconnecting said generator field winding at a predetermined motor speed and reconnecting said field winding to the armature terminals of said generator with reverse polarity to effect stopping of said motor.
